Jerome V. Benson and Edward F. Felien,
Duluth, Minn.

Application June 23, 1945, Serial No. 120,287

Term of patent 3½ years

(Cl. D34—15)

To all whom it may concern:

Be it known that we, Jerome V. Benson and Edward F. Felien, citizens of the United States, residing at Duluth, in the county of St. Louis and the State of Minnesota, have invented a new, original, and ornamental Design for a Rocking Horse, of which the following is a specification, reference being had to the accompanying drawing, forming part thereof.

Fig. 1 is a perspective view of a rocking horse, showing our new design.

Fig. 2 is a front elevational view of Fig. 1.
We claim:

The ornamental design for a rocking horse, as shown.

JEROME V. BENSON.
EDWARD F. FELIEN.
